(57) **CLAIM**

I claim the ornamental design for a crustacean pliers, as shown.

DESCRIPTION

FIG. 1 is a front elevational view of a crustacean pliers showing my new design;

FIGS. 2 and 3 are respectively top plan and right side elevational views thereof;

FIG. 4 is a bottom plan view thereof;

FIG. 5 is a left side view thereof, the crustacean pliers having rotated 180° about a horizontal center line; and,

FIG. 6 is a rear elevational view thereof.
